UNITED STATES PATENT OFFICE

AMADEO RIPOLL, OF BARCELONA, SPAIN

TAXIMETER

Application filed September 14, 1929, Serial No. 392,687, and in Spain September 17, 1928.

The present invention relates to a taximeter having a number of advantages over known apparatus, such as robustness and simplicity of the mechanism, its compactness, the precision of its indications, and the total impossibility of the perpetration of fraud in its use.

Apparatus according to the invention is illustrated by way of example in the accompanying drawings.

Figure 1 is a front view of the apparatus.

Figure 2 is a side view of the exterior of the apparatus.

Figure 3 is a vertical cross-section of the apparatus, showing the interior.

Figure 4 is a detail in vertical section of the means employed for effecting the change of tariff.

Figure 5 is a section of details of the connection of the transmission cable from the wheels of the vehicle to the mechanism of the apparatus.

Figures 6, 7 and 8 are details of the actuating mechanism of the transmission cable.

Figure 9 is a vertical section from the rear of the apparatus.

Figure 10 is a plan.

Figure 11 is a side elevation taken at the side at which the flag lever is disposed, that is to say at the side opposite to that of Figure 3.

Disposition of the apparatus

Figure 1 shows the front of the apparatus, with the flag 1 in the "free" position, that is to say raised. All the mechanism is mounted on a solid base 2 and is advantageously protected by a box 3 fixed to the base by means of four lead sealed screws 4. Such a disposition of the box prevents all access from the exterior, leaving only passage for the spindle of the flag 5, the spindle for resetting the clockwork movement 6 and the spindle for the key 7 for recording the supplements or extras. A pane of glass 8, advantageously fastened by a frame 9 fixed on the box allows a plate 10 to be seen, which is provided with apertures which permit the reading of the various indications corresponding to the function of the apparatus,

such as: "Fare" 11, "Extras" 12, the counter for "Extras" 13, rate employed indicator 14, the fractions counter 15, counter for the lowering of the flag 16, total distance covered 17 and counter of distance covered with flag 18 lowered 18.

The base carries two arms 21 for fixing the apparatus to the vehicle, it also carries a boss 22 which supports a terminal 23 by means of which the cable actuates the mechanism of the apparatus. The said terminal is coupled at the lower end of the first spindle 24 (Figure 4) by means of a friction coupling, in order that when the mechanism of the apparatus presents an abnormal resistance, the revolutions of the flexible cable cease to be transmitted to the counter, thus avoiding any breakage.

The apparatus hereinbefore described is operated by a flexible cable 25 (Figures 6, 7 and 8) connected at one of its ends to the apparatus and at the other to a toothed pinion 26 which by means of the spiral ring 27, placed on one of the wheels of the vehicle, causes the pinion to advance by a tooth at each rotation of the said wheel. In order that the friction produced by this operation is noiseless the said pinion may advantageously be constructed of fibre.

According to circumstances a reducing gear 28 may be applied to the speed gear for replacing the pinion.

The apparatus has a clockwork movement destined to actuate the fare mechanism when the flag is lowered and the vehicle stopped.

The principal characteristics of the apparatus are the following:

The wheel 46 (Figure 9) is rotated either by the clockwork or by the cable which is coupled to the speed gear or operated from one of the wheels of the vehicle. The wheel 46 is fixed to its spindle 47 and transmits rotation to the wheel 49, which is mounted freely upon its spindle 50. A toothed crown is fixed to the wheel 49 and engages a toothed collar loose on the spindle 50 and fixed by one of its extremities to the helical spring 51. The operation of the crown has for its effect to graduate the force exerted by the escapement spring. The other extremity of

the spring 51 is secured to the spindle 50 by means of a drum 52. A cylinder or disc 48 with projections is secured to the spindle 47, and the projections, in the rotation, strike 5 against the projections of a cylinder or disc 53, which is secured to the spindle 50. When the spindle 47 has effected a turn of 90° the projections of the cylinder or disc 53 strike against the projection of the cylinder or disc 10 48, and, at this moment, by reason of its operation, a sharp escapement is produced by the increasing pressure of the spring 51. At the moment of the escapement, one of the 15 projections of the cylinder or disc 53 which travel over the periphery of the cylinder or disc 48 is applied against the interior face of the said cylinder or disc. In the following escapement it detains the other of the 20 projections of the cylinder or disc 53 by the periphery of the cylinder 48, the said escapement being repeated successively for each unit of the drum indicators of the charge for the journey.

25 A pinion 73 (Figure 9) secured to the spindle 50 engages with the pinion 74 (Figure 10) which carries solid with it a pinion 70 engaging with the pinion 72 and serving to transmit the escapement hereinbefore described to the drums 71 indicating the 30 charge for the journey. These pinions always maintain in position the drums indicating the charge for the journey, so that, even though the glass of the apparatus be broken, it is not possible for the charge indicated to be altered, by reason of the mechanism provided.

Figure 11 represents the taximeter in the "free" position. On lowering the flag to the "engaged" position or to adjust the taximeter 40 to one or other of the tariffs for which it is adapted, the rotation of the wheel 55 is effected and is transmitted to the pinion 63 by means of the intermediate wheels 56, 59 (situated behind the wheel 61) and 61. This 45 rotation is effected in order that the projection 64, with which the pinion 63 is provided, may engage a recess with which the lever 65 is formed, and this lever, subject to the action of the eccentric 60 (situated behind the wheel 61), descends at the precise 50 moment to engage the projection 64.

The wheel 61 is only toothed for a portion 55 of its periphery in order to ensure that the pinion 63 shall not turn beyond a certain angle although the flag spindle may be turned through an angle greater than that corresponding to the first tariff where it is necessary to pass to a higher tariff.

60 The pinion 63 is rigid with the spindle 66 which by consequence partakes of the movement of the pinion; by reason of the presence of the spring 75 (Figure 10) which is fixed by one extremity to the spindle 66 and 65 by the other extremity to a point of the

frame plate, energy is stored in this spindle 66 when it is rotated.

At the same time that the operations indicated take place rotation of the wheel 57 is effected from the wheel 55 through the intermediate wheel 56. This rotation has for its purpose to cause the pin or projection 67 with which the wheel 57 is furnished to set free the lever 68, and the spindle 69 which carries the pinions 70 is then axially displaced under the action of a spring placed at one extremity so that the pinions 70 come into engagement with the teeth 72 of the numeral drums 71 (Figure 10). These drums are mounted freely on their spindle 66 and are rotated by the action of the said pinions 70.

85 The spindle 66 on which are mounted the drums 71 is furnished with a longitudinal recess extending for the whole of the space occupied by the drums, and these carry at the interior small pawls with corresponding springs that are disposed in such manner that when the drums turn in the direction in which they are operated by the pinions 70, the pawls pass without difficulty the longitudinal recess of their spindle 66 but do not pass if the drums turn in the contrary direction since in this case they are engaged 90 in the said recess.

95 The manner in which the indication of the cost of the journey is effaced may now be followed.

100 In raising the flag to the position "free" there is produced a rotation of the wheel 55 in the direction contrary to that when the flag was lowered. This rotation is transmitted by the wheel 56 to the wheel 57 where by the pin or projection 67 takes up a position below the lever 68 causing the spindle 69 to be displaced axially and with it the pinions 70 which thus pass out of engagement with the numeral drums and leave them 105 consequently free on their spindle. At the same time the wheel 56 transmits its rotation to the cam 60 and the latter causes the lever 65 to rise sufficiently to render free the projection 64. At this moment there comes into 110 action the stored energy of the spring 75 which tends to cause rotation of the spindle 66 of the drums in such manner that the pawls provided in the interior of the drums remain engaged in the longitudinal recess of the said spindle 66 and thus the drums participate in the rotation of their spindle, the 115 cost of the journey being thus effaced. To secure that the drums shall be arrested in the position corresponding to the initial price they are provided with small abutments 76 (Figure 10) which come into contact with the stops 77 rigid with their spindle 78 which at this moment, under the action of the eccentric 80 (Figure 3), which rotates following the movement of the flag, is caused to 120 take a position in which the stops 77 descend 125

sufficiently to make contact with the abutments 76.

Having now particularly described and ascertained the nature of my said invention and in what manner the same is to be performed, I declare that what I claim is:—

In a taximeter, the combination of a spindle, numeral drums carried loosely on the spindle, a pinion rotated from the flag spindle and rigid with the said spindle and hav-

ing a projecting stud, a spring acting against the rotation of the pinion in one direction, a pawl provided to engage the said stud, a second spindle parallel with the first spindle and carrying rigidly thereon stops, projections related to the numeral drums and adapted to engage the said stops, a lever fixed upon the spindle provided with the stops, and a cam for operating the said lever.
